CONTROL MEANS FOR AIR CIRCULATING SYSTEMS

Norman Passur, Oakland, Calif.

Application February 15, 1938, Serial No. 190,622

3 Claims. (Cl. 98—39)

This invention relates to air circulating systems of the type used in the heating, cooling, and air conditioning of buildings, vehicles, and other inclosed spaces.

The principal object of the invention is to provide means for automatically controlling the relative amounts of air taken in and mixed from two sources, according to the temperature of one source, in order to prevent overloading the

10 heating or cooling functions of the system. A second object is to provide automatic control means which will operate in response to both high and low temperatures. A third object is to provide an automatic means which will control the amount of power used in moving the air, in order to prevent waste thereof. Still further objects and advantages of the invention will be apparent from the following specification, which should be read with the understanding that changes, within the limits of the claims hereto appended, may be made in the form, construction and arrangement of the various parts, without departing from the spirit of the invention.

The invention is particularly useful in connection with air conditioning systems in railway and other vehicles, although it is in no sense limited thereto, and may be used with equally good results in heating, cooling or ventilating systems in buildings or other inclosed spaces.

The accompanying drawing is a diagram illustrating the functional relations between the several elements of the invention. The positional relation of said elements as shown is for illustration only, and is not material to the invention.

Referring to the drawing, the reference numeral 1 designates the interior of an inclosed space, such as a railway car or a room in a building, having walls 2. 3 is a fresh air inlet opening in one of said walls for admitting air from the outside atmosphere into an inclosed mixing chamber 4. 5 is an air inlet opening for admitting air to said mixing chamber 4 from the interior of the vehicle or room 1. 6 is a fan for circulating the air, said fan sucking the air in through either or both inlets 3 and 5 and discharging it at 7 into the interior of the car or room. 8 is a separate booster fan driven by an electric motor 9, which operates only on the air entering through the outside inlet 3.

The parts described above are common and well known, and cooperate to form the usual air circulating system by which the air in an inclosed space is caused to circulate and be freshened by outside air drawn in more or less continuously

and mixed with the interior air. Washing and filtering means may be included in the system at suitable points, but such means, being well known in the art, have been omitted from the drawing. A radiator or absorber, which may be used either for heating or cooling the air, is represented at 10.

A system of the type described above will not operate successfully or economically when the outside atmospheric temperature is subject to wide variations between extremes of heat and cold. If the areas of the outside and inside air inlets 3 and 5 are so designed as to supply fresh and recirculated air in fixed proportions, the amount of fresh air, even though it be the minimum necessary for proper ventilation, is so great as to require excessive capacity in the cooling and heating apparatus when the outside temperature rises above or falls below a middle or moderate range, say for example between 75° F. and 40° F.

The present invention meets this difficulty by providing an excess of outside air during such times as the outside temperature is within a moderate range, say between 75° F. and 40° F., so that 25 during such times the air in the car or room is freshened to a greater extent than necessary, and then increasing the proportion of recirculated air when the outside temperature exceeds these limits, so that less cooling or heating capacity is required. This system is especially useful in railway and other vehicles, where both space and available cooling and heating power are limited, and where due to mobility, extremes of temperature do not persist for any great length of time. 30

The proportioning of the air supply, as between outside fresh air and recirculated inside air is accomplished, automatically, in the following manner. The inside air inlet 5 is provided with 40 a shutter 11, shown in the diagram as composed of a plurality of movable vanes, which shutter is opened and closed by a rod 12 operated by a solenoid 13. It is assumed that the weight of the rod 12 closes the shutter 11 when the solenoid 13 is not energized, and that said solenoid, when energized by current supplied from a source 14 through wires 15, opens the shutter.

Two thermostatic switches 16 are positioned in the fresh air inlet 3, where they are affected by the temperature of the outside atmosphere. The contacts 17 of said thermostats are connected in parallel by wires 18, and are included in series in the circuit of the solenoid 13. Therefore when the contacts 17 of either thermostat are closed, the solenoid 13 is energized and the shutter 11

is opened. One of the thermostats 16 is set to close its contacts when the temperature of the atmosphere rises above a predetermined maximum, say 75° F. and the other thermostat is set 5 to close its contacts when the temperature of the atmosphere falls below a predetermined minimum, say 40° F. Therefore, whenever the atmospheric temperature rises above 75° F. or falls below 40° F., the shutter 11 will be opened, and 10 recirculated air admitted through the inlet 5 to the mixing chamber 4, but when the atmospheric temperature is between the above limits, i. e. when it is in a moderate range, the shutter 11 remains closed and all the air is supplied from 15 outside through the inlet 3.

A manually controlled shutter 19, operated by a rod 20 having a handle 21, is provided in the fresh air inlet 3 for closing the same when necessary, as for example when a railway car is 20 passing through a tunnel and outside air must be temporarily excluded. The rod 20 of the shutter 19 operates a pair of contacts 22 connected with the wires 18 in parallel with the thermostat contacts 17, so that the recirculated air shutter 11 is automatically opened whenever the manual 25 fresh air shutter 19 is closed.

A magnetic relay 23 is included in the circuit of the solenoid 13, and the contacts 24 of said relay control the motor 9 of the fresh air booster 30 fan 8, said motor being operated by current supplied by wires 25. The relay 23 is so arranged that its contacts 24 are open when the solenoid circuit is energized, so that the booster fan 8 35 operates only when the recirculated air shutter 11 is closed and all the air is being supplied through the fresh air inlet 3. When the recirculated air shutter 11 is open, or when the manually operated fresh air shutter 19 is closed, the booster fan 8 is idle. This not only economizes 40 on power, but also reduces the amount of fresh air drawn in when the recirculated air inlet is open. The respective inlets 3 and 5 are so proportioned that, when the fan 8 is idle, the

amount of fresh air drawn in through inlet 3 is not enough to overload the cooling or heating capacity of the coil 10.

I claim:

1. In an air circulating system having an inlet 5 for fresh air and an inlet for recirculated air, a movable shutter for said recirculated air inlet, electromagnetic means for operating said shutter, a thermostatic switch responsive to the temperature of the air outside said fresh air inlet for controlling said electromagnetic operating means, a separately movable shutter for said fresh air inlet, and a switch connected with said fresh air shutter and operated by the movement thereof for controlling the operating means of 10 said recirculated air shutter.

2. In an air circulating system having an inlet 10 for fresh air and an inlet for recirculated air, an electric fan in one of said inlets, a movable shutter for said recirculated air inlet, electromagnetic means for operating said shutter, a thermostatic switch responsive to the temperature of the air outside said fresh air inlet for controlling said electromagnetic operating means and said fan, a separately movable shutter for 20 said fresh air inlet, and a switch connected with said fresh air shutter and operated by the movement thereof for controlling said fan and the operating means of said recirculated air shutter. 30

3. In an air circulating system having an inlet 35 for fresh air and an inlet for recirculated air, a movable shutter for said recirculated air inlet, means for operating said shutter, means responsive to the temperature of the air outside said fresh air inlet for controlling said shutter operating means, a separately movable shutter for said fresh air inlet, and means connected with said fresh air shutter and operated by the movement thereof for controlling the operating 40 means of said recirculated air shutter.

NORMAN PASSUR.
